UNITED STATES PATENT OFFICE.

VIRGINIUS Z. CARACRISTI, OF BRONXVILLE, NEW YORK.

APPARATUS FOR FEEDING PULVERIZED FUEL.

1,192,386.

Specification of Letters Patent. Patented July 25, 1916.

Application filed July 23, 1914, Serial No. 852,771. Renewed June 12, 1916. Serial No. 103,343.

To all whom it may concern:

Be it known that I, VIRGINIUS Z. CARACRISTI, a citizen of the United States, and a resident of Bronxville, in the county of 5 Westchester and State of New York, have invented certain new and useful Improvements in Apparatus for Feeding Pulverized Fuel, of which the following is a specification.

10 This invention relates to apparatus for feeding pulverized fuel, as for instance, coal dust or comminuted coal, and has for its object to provide an improved apparatus by the use of which the fuel falling on a stream 15 of air is carried by the same, and while being thus supported, is completely enveloped by the stream of air, and simultaneously carried forward by the same, whereby a thorough mixing of a maximum amount of 20 pulverized fuel with the least possible amount of air is accomplished.

In carrying out the invention, and in the actual use of the same, a return screw for unfed fuel is not needed, as the stream of 25 air is intended to prevent the dropping of the fuel through the stream, a return screw, however, being provided in the event that the flow of the stream of air should be interrupted.

30 A further object of the invention is to provide a very compact apparatus which is obtained by arranging the main feed-screw and auxiliary return feed-screw in a direction parallel with the air feeding means and 35 in line with the fuel and air mixture outlet.

One of the features of my invention is to provide a stream of air wider than the stream of falling fuel, and which fuel is forced in the same direction as the direction 40 of the air stream, utilizing thereby the energy transmitted to the fuel feed, and at the same time providing a maximum amount of skin surface without unduly increasing the volume of the air supply, the stream of 45 air acting substantially like a rigid column, but having an upper gathering surface embracingly supporting the fuel.

The invention is shown in the accompanying drawings, in which several embodiments 50 are shown, and it will be more fully described hereinafter and finally pointed out in the claims.

In the accompanying drawings, Figure 1 is a vertical longitudinal section of my im- 55 proved apparatus showing the superposed and parallel feed-screws, air feeding means,

and fuel and air mixture outlet, all arranged longitudinally of the machine, Fig. 2 is a vertical transverse section taken on line 2—2 of Fig. 1, showing a U or cup-shaped air 60 outlet orifice, Fig. 3 is a vertical transverse section of a modified form of air orifice, with the upper surface substantially plane, Fig. 4 is another modified form, having the upper surface parallel with the lower surface, 65 Fig. 5 is still another modified form showing a plurality of superposed crescent-shaped air orifices, Fig. 6 is another modified form of air orifices, showing a plurality of upright teeth forming a plurality of pockets 70 laterally arranged, Fig. 7 is a section taken on line 6—6 of Fig. 1, intended to show the relative position of the fuel and air-stream at the time when the fuel drops on the stream of air, Fig. 8 is a section taken on 75 line 8—8 of Fig. 1, showing the stream of air warped or molded to completely surround the fuel as it is about to emanate from the outlet chamber.

Similar reference characters indicate corresponding parts throughout the various figures of the drawings.

Referring to the drawings, and more particularly to Fig. 1, my improved apparatus comprises a feed-hopper 10, below which is 80 arranged a main feed-screw 11, one end of which is rotatable in bearings 12 and is secured to an operating gear-wheel 13, while the other end is rotatable in bearings 14. At this end an opening 15 in the feed-screw 85 casing 16 is arranged at a point below the feed-screw, which opening permits the fuel fed by the main feed-screw 11 to pass therethrough. This opening is arranged in the form of a longitudinal elongated slot, as is 90 clearly shown in Fig. 2, the object of which is to shape the fuel passing therethrough, so that it may take substantially the shape of a cross section of the slot when falling. At the same time, the momentum imparted to 95 the fuel by the forward-feeding action of the main feed-screw 11 gives the fuel so fed through the elongated slot 15 a forward movement in the direction of the arrow 18. Below the main feed-screw 11 is arranged 100 an air supply-nozzle 20, which has its orifice 21, in the embodiments shown in Figs. 1 and 2, in the shape of a U or cup, with the open end upwardly arranged.

The force of the air emanating from the 110 nozzle 20 out of the orifice 21, is such as to maintain the stream in the shape of the

orifice, and therefore provide an elongated U or cup-shaped substantially rigid stream, which extends from the orifice 21 through the chamber 23, its direction being indicated 5 by the arrows 18^a, 18^b, 18^c and 18^d. Tangential to the lower surface of the cup-shaped stream thus formed, a plate 24 is arranged, which has an inclination to the horizontal, so that the stream will continually impinge against this inclined plate 24 and remove therefrom any fuel that may 10 otherwise gather on the plate 24. At the same time, the object of this inclination is to have the plate act to "gather in" the 15 expanded stream of air. By the inclination, the surrounding casing 23 is of larger cross-section than that of the expanded stream at that point. This plate 24 has a circular cross section which is tangential to the periphery of the cup-shaped stream, and forms with the outlet 25, a converging outlet chamber 26, which serves to add to the velocity and at the same 20 time guides the stream in such a manner that the upper ends of the U are caused to be united, whereby an elongated hollow stream is produced, which completely 25 envelops the mass of fuel carried in the center thereof, and moving in the direction of the 30 arrow 18^e.

Below the air orifice 21, an auxiliary screw 28 is provided, which has one end rotatable in bearings 29 and the other end in bearings 30, and is secured at that end with 35 the gear-wheel 31, which meshes with the gear-wheel 13. Also secured to the shaft of the screw 28 is a gear-wheel 32, which meshes with a pinion 33 operated by a suitable motor 34, arranged below the auxiliary screw 28, as also below the casing 16, the hopper 10, the main screw 11 and the air nozzle 20. It will be noted that the gear 31 is smaller than the gear 13, by reason of 40 which the speed of the main screw 11 is less than the speed of the auxiliary screw 28. This is advantageous because it is desirable to feed any fuel that may have been dropped on to the auxiliary screw 28 quickly 45 away from the chamber 23. The auxiliary screw 28 is intended to be used to quickly remove the fuel which is dropped on to it, in the event that the flow of the air stream is interrupted, as when the air stream is in 50 proper operation all the fuel is intended to drop on to the stream and be immediately carried away thereby. But by removing any fuel that may have dropped, the air stream, when it again is active, is not in any 55 way influenced in its shape, or has the shape which it receives at the time it emanates from the orifice 21 distorted by conflict with any fuel which may have gathered at the lower part of the chamber 23, or on the deflecting plate 24. It will be noted that the 60 65 inclination of this plate serves also to cause

the fuel to slide off and downwardly on to the auxiliary screw 28. Any fuel that should drop on the screw 28 is fed by the same into the upwardly-curved chamber 36, formed by the casing 36^a, to be taken up by 70 the main feed-screw 11 to be again fed forwardly toward and through the elongated fuel discharge opening 15. To prevent any pressure in the hopper 10 exerted by the fuel fed upwardly by the auxiliary 75 screw 28, a deflecting plate 37 is arranged in the hopper 10, which serves to guide the fuel in the direction of the feed of the feed-screw 11, and at the same time, due to the space formed beneath it, prevents any fuel 80 from causing a choking action on the fuel fed upwardly by the auxiliary screw 28. It is noted, however, that the screw 28 is not absolutely essential during the efficient 85 operation of the apparatus, for the reason that the air stream, by virtue of the shape that has been given to it, carries all the fuel fed through the elongated orifice or fuel discharge opening 15 forwardly into the outlet chamber, and thereby prevents 90 any fuel from falling on to the auxiliary screw. But in the event of the failure of the air nozzle, it is important to have the screw 28, so that the apparatus may continue to operate without injury to it, or 95 without causing any choking action thereof until the air supply is again re-established, and the normal operation of the apparatus again carried out.

The air nozzle 20 is provided with an air 100 supply conduit 20^a, which extends longitudinally of the apparatus, and then is bent as shown by 20^b, toward the center part of it.

It will be noted that in my improved apparatus, the main feed-screw 11, the air orifice 21, and the air stream emanating therefrom, the chamber 23, the return auxiliary screw 28, as also the axis of the motor if it is so desired, all are arranged in the same direction longitudinally of the apparatus. 105 This provides a very compact structure, and at the same time provides the advantage that the air flow and fuel flow are in the same direction and not transversely to each other, whereby the efficiency of the apparatus is increased by reason of utilizing all the forces acting on the fuel, and not having any loss brought about by a change of direction of forces.

The especial advantage of the cup-shaped stream is that it provides a large skin action of the air on the fuel supported thereby and the fuel is supported by this stream of air with the large contacting surface and is carried forwardly thereby. Gradually and finally, the fuel is completely enveloped by the stream of air, and due to the increased velocity, it arrives at the discharge opening completely surrounded by the envelop of air. This permits the economical handling of the 120 125 130

pulverized fuel by the air, brought about by the fact that all of the valuable energy in the air is utilized, the velocity of the air of necessity being so great so as to carry the fuel as described.

In the embodiment shown in Fig. 3, a stream of air having a vertical transverse section of semi-circular shape is provided by the configuration of the orifice 40 shown in Fig. 3. This orifice has an upper straight surface 41 and a lower surface 42 semi-circularly curved.

In Fig. 4, the orifice 45 is shaped to form a stream of air having the top and bottom thereof parallel, whereby the upper surface may catch the falling fuel. The upper surface of the orifice 45 is straight as indicated by 47 and the lower surface 46 is also straight.

In Fig. 5 is shown an orifice with a plurality of superposed pocket like orifices, formed by means of crescent-shaped air streams. It will be noted that the upper orifice 50, in the embodiment shown in Fig. 5, is somewhat thinner than the lower orifice 51, and the advantage of this is that the upper pocket will serve to support and carry fuel, but will gradually permit the fuel to pass therethrough, and drop on to the second pocket, and then be supported and carried by the lower pocket. By this initial permeation, the efficiency of the ultimate mixture of fuel and air is materially effected. It will also be noted that by these superposed pockets, which are in the embodiment shown in Fig. 5 vertically arranged, large skin contacting surfaces are provided, so that the largest amount of fuel may be distributed over the large area of the air stream.

In Fig. 6 is shown an embodiment with laterally-arranged pockets, whereby a large skin action and surface is arranged. The orifice 60 has teeth 61, 62, 63 and 64 at the upper surface thereof, and a circular configuration 65 at the lower surface thereof. Of course, the shape of the teeth may be changed as desired, and also superposed air streams of similar configuration may be provided.

In Fig. 7 is shown the intended coöperation of the stream of air, indicated by 71 and the fuel indicated by 70, just at the moment when the fuel falls on to the stream of air. By the flow of the stream of air into the converging chamber 26, the end portions of the air stream are caused to envelop the fuel as the envelop 82 of air, completely surrounding the fuel 81, in Fig. 8, shows. The fuel depresses somewhat the air, as is indicated in Fig. 7, and similarly, when using the orifices shown in the embodiments of Figs. 3 and 4, the upper plane surfaces are somewhat depressed by the weight of the fuel, so that by reason thereof the stream of air really serves to embracingly support the

fuel, somewhat analogous to the curved or cup-shaped embodiments of Figs. 1, 5 and 6.

These various embodiments shown in Figs. 1 to 6, become especially important, when it is remembered that experience has demonstrated that a solid cylindrical column of air, having no upper gathering surface, will not efficiently handle as much fuel per unit of air as when greater skin surface is provided, as in the case of the prior art solid cylindrical columns, which have a convex upper surface, the fuel would be deflected and drop off, instead of being carried by a stream having an upper gathering surface, and hence at the mixing point insufficient mixtures would be obtained.

Thus, from the above it appears that the means for feeding the air, one embodiment of which is indicated by 20, the means for shaping the air, one embodiment of which is indicated by 21, the means for delivering the fuel, one embodiment of which is indicated by 15, the means for enveloping the air, one embodiment of which is indicated by 26, and the means for accelerating the air, one embodiment of which is shown by the inclination given the part 26, all co-operate in the manner described.

I have used the word periphery, by which I mean the external surface of the air-stream, or outside edge of the air.

I have shown several embodiments of my invention, but it is clear that changes may be made therein without departing from the spirit of the invention as defined in the appended claims.

I claim:

1. An apparatus for feeding pulverized fuel, comprising means for feeding a stream of air in a shape and state to form an upper supporting gathering surface, means for guiding said stream of air, and means for delivering on the upper supporting gathering surface of the stream of air in the guiding means quantities of fuel to be carried by the air stream.

2. An apparatus for feeding pulverized fuel, comprising means for feeding a stream of air in a shape and state to form an open upper supporting gathering surface, means for guiding said stream of air, means for delivering on the top of the open upper supporting gathering surface of the air in the guiding means quantities of fuel to be carried by the air stream, and means for shaping the air stream to envelop the fuel delivered on its upper supporting surface.

3. An apparatus for feeding pulverized fuel, comprising means for feeding a stream of air, means for shaping the stream of air to form an upper supporting gathering surface, means for guiding the air stream, means for delivering in the guiding means on the upper supporting gathering surface of the air stream quantities of fuel to be

carried by the air stream, means for shaping the air stream to envelop the fuel delivered on its open upper supporting surface for completely enveloping the same, and means 5 for simultaneously accelerating it.

4. An apparatus for feeding pulverized fuel, comprising means for feeding a stream of air, means for shaping said stream of air to form an open upper supporting gathering 10 surface, means for guiding the air stream, means for delivering in the guiding means on the top of the open upper supporting gathering surface of the air quantities of fuel to be carried by the air stream, means 15 for shaping the air stream to envelop the fuel delivered on its upper supporting surface for completely enveloping the same, and inclined plates in the path of the air current, impinged by the periphery of the 20 air stream for increasing the speed of movement of the air stream and fuel enveloped thereby.

5. An apparatus for feeding pulverized fuel, comprising means for feeding a stream 25 of air in a shape and state to form an upper supporting gathering surface, means for guiding said stream of air, means for delivering on the top of the upper supporting gathering surface of the air in the guiding 30 means, quantities of fuel to be carried by the air stream, and means for simultaneously imparting to the fuel while being delivered to the air stream a movement in the same direction as the stream of air.

35 6. An apparatus for feeding pulverized fuel, comprising means for feeding a stream of air in a shape and state to form an open upper supporting gathering surface, means for guiding said stream of air, means for 40 delivering on the top of the open upper supporting gathering surface of the air in the guiding means quantities of fuel to be carried by the air stream, and a delivery opening 45 of a shape narrower than the width of the air stream for shaping the stream of fuel

and for giving to the stream of fuel a width narrower than the width of the air stream when the fuel is gathered on the air stream.

7. An apparatus for feeding pulverized fuel, comprising means for feeding an air 50 or gaseous stream, means for imparting to the fuel an initial travel, means for guiding said stream of air, and means for imparting to the air or gaseous stream a shape and state to receive and support and convey the 55 fuel while being delivered in the guiding means, the travel of the fuel stream and air stream being in the same general direction as the delivery of the combined fuel and air.

8. An apparatus for feeding pulverized 60 fuel, comprising means for producing a stream of air, means for guiding a stream of air, means for feeding fuel in the same direction as the stream of air in the guiding means, means for delivering the fuel in the 65 same direction as its feed, and positive moving means for imparting to it an initial movement in the direction of the stream of air.

9. An apparatus for feeding pulverized 70 fuel, comprising means for producing a stream of air, means for guiding a stream of air, means for feeding fuel to the air stream in the same direction as the stream of air in the guiding means, means for delivering the 75 fuel in the same direction as its feed, moving means for imparting to it an initial movement in the direction of the stream of air, and means for reforming the stream of air into a cylindrical envelop completely sur- 80 rounding the fuel and accelerating the movement of the stream of air while thus enveloping the fuel.

In testimony, that I claim the foregoing as my invention, I have signed my name in 85 presence of two subscribing witnesses.

VIRGINIUS Z. CARACRISTI.
